Primary Examiner — Selina Sikder(74) *Attorney, Agent, or Firm* — Keating & Bennett, LLP(57) **CLAIM**

The ornamental design for an axial flow fan, as shown and described.

DESCRIPTION

FIG. 1 is a front elevation view of an axial flow fan according to our principal new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a perspective view thereof.
